UNITED STATES PATENT OFFICE.

JOSEPH H. SCHWEICH, OF ST. LOUIS, MISSOURI.

MANIFOLDING DEVICE.

No. 926,212.

Specification of Letters Patent.

Patented June 29, 1909.

Application filed May 11, 1908. Serial No. 432,268.

To all whom it may concern:

Be it known that I, JOSEPH H. SCHWEICH, a citizen of the United States, residing at the city of St. Louis, State of Missouri, have invented a certain new and useful Improvement in Manifolding Devices, or Devices for Making Copies of Bills, Letters, &c., of which the following is a specification, reference being had to the accompanying drawings, forming part of this specification, in which—

Figure 1 is a plan view of my improved manifolding device, partly broken away to show the record sheet and platen or writing surface; Fig. 2 is a cross-sectional view on the line 2—2, Fig. 1; Fig. 3 is an enlarged detail sectional view, showing the paper guiding-clip and the holding-frame in open position; Fig. 4 is an enlarged detail sectional view, showing a portion of the transferring and record sheets and of the holding-frame and also the locking means for locking said frame in closed position; and Fig. 5 is an enlarged side elevational view of a portion of my manifolding device, showing the spacing member and the clutch mechanisms for holding the paper-clip and pointer or indicator in adjusted positions.

This invention relates to a new and useful improvement in manifolding devices or devices for making copies of bills, letters etc.

My device is especially adapted for making copies by means of carbon or other transferring paper of bills, letters, etc., when written by hand, such bills or letters being transferred on to what I call a record sheet, which, when completely filled, is designed to be removed from the machine and preserved, preferably in a loose-leaf binder or the like, so that a compact and easily-accessible record of all such bills or letters may be kept.

While my device may be used for making copies of any papers or documents, when written by hand, its operation is herein shown and described in connection with making copies of merchandise bills, for which use it is particularly adapted, one of the main objects of my invention being to fully utilize the record sheet, a bill or bills being transferred thereunto until the same is completely filled, and thus not only is the entire surface of each record sheet utilized, but also the number of record sheets is economized, and as the figures entered in the dollars and cents columns of the several original bills will be transferred onto said record sheet in like columns, the complete addition on said

record sheet of the figures entered on said respective original bills will be facilitated.

With the above objects in view, my invention consists in the novel construction, combination, and arrangement of the several parts of my manifolding device, all as will hereinafter be described and pointed out in the claims.

In the drawings, 1 indicates the base-plate, on which is arranged a writing-plate or platen 2, preferably of zinc, so as to provide a smooth writing surface upon which the record sheet A is adapted to be placed.

3 indicates guides located adjacent the inner edge of the plate or platen 2, see particularly Fig. 3. The guides 3 are preferably resilient members having hooked end portions 4, under which one edge of sheet A is adapted to be inserted. These guides 3 are mounted in recesses 5 in the base-plate 1, so that the same may be depressed, as herein-after described. It is preferable to also provide pins 6 a slight distance above the top of platen 2, by which the record sheet A is so perforated to assist in holding said sheet A in position, but said pins 6 may be dispensed with, if desired.

Hinged to the base-plate 1 at one side of the platen 2 is a rectangular frame 7, which is adapted to surround said platen when folded down against the base 1. This frame 7 is arranged to overlap the edges of the record sheet A when on the platen 2 (see particularly Fig. 4) and thereby hold the same in position, guides 3 being depressed in the recesses 5 by said frame when in closed position and the pins 6 entering perforations provided therefor in the frame 7.

Hinged to frame 7 is a frame 8, which is preferably similar to frame 7, the carbon or other transferring sheet B being designed to be placed between said frames 7 and 8, and the free ends of said frames 7 and 8 being releasably held together by a spring-catch 9, which, when said frames are in lowered position, fits in a recess 10 provided therefor in the base 1. Frames 7 and 8, when fastened together, move as one frame and constitute a holding device for the carbon or other transferring sheet B, which, as before stated, is placed and held between the frames 7 and 8. When the frames 7 and 8 are in lowered position, the top surface of frame 8 is preferably flush with the surface of the platen 2, so that the sheet B rests smoothly thereupon above the record sheet A.

11 indicates latches or other locking means provided at the side of base 1 and which are adapted to lock the frames 7 and 8 in folded or lowered position on the base 1, whereby 5 the copying sheet B and record sheet A are firmly held in proper operative position. Preferably the edges of the platen 2 are rounded or beveled, and the inner lower edges of the frames 7 and 8 are beveled or undercut 10 to avoid crimping or creasing the edges of the record sheet A and copying sheet B when the frames 7 and 8 are locked in closed or lowered position (see particularly Fig. 4), said frames and platen being so designed that the dropping or lowering and locking of said frames 15 to said base will cause the sheets A and B to be drawn tightly across said platen, whereby a smooth writing surface is provided.

Near the top and bottom and at one side of 20 frame 8 (see Fig. 1), are placed studs 12, in which is mounted a guide-rod 13, preferably rectangular in cross-section, extending along one side of the top of frame 8.

14 indicates a spring-clip designed to hold 25 the bill or the like C upon which the original entries are to be made. This clip 14 is provided with an extension 15, on which is secured a sleeve portion 16 designed to fit and slide upon the rod 13. Said extension 15 is 30 also provided with a friction clutch (see particularly Fig. 5) comprising two oppositely-disposed members 17 and 18 designed to hold said clip 14 in adjusted positions on said rod 13. These members 17 and 18 have a pivotal slot-and-pin connection with the extension 15 and are each provided with an off-set portion 19, said portions 19 being each provided with an opening to slidingly fit the rod 13. The members 17 and 18 are normally 35 held apart by the spring 20, in which position the off-set portions 19 are canted so as to cause the walls of the openings or perforations therein to bind on the rod 13 and frictionally hold the clip 14 in adjusted positions 40 on said rod 13, for purposes hereinafter stated. When it is desired to adjust or move the clip 14 to various positions along said rod 13, the clutch members 17 and 18 are brought together against the tension of spring 20 45 until said off-set portions 19 are brought substantially perpendicular to the axial line of said rod 13, at which time said clip 14 may be shifted lengthwise of the rod 13. Thus said clip 14 may be placed in any position along 50 the rod 13, so as to hold the bill or other paper in proper place where the items entered thereon may be transferred therefrom onto some unused portion of the record sheet A. Said clip 14 is further provided with a paper- 55 guide 21, against which the edge of the bill or other paper is adapted to abut to properly position the same. 22 indicates a pointer, which is provided with a sleeve portion 23 designed to slidingly fit said rod 13. This 60 pointer 22 is also provided with a friction

clutch 24, somewhat similar in action to the above-described clutch members 17 and 18, said clutch 24 having also a slot-and-pin connection with the pointer 22, and said clutch 24 having a bent portion 25, which is provided with an opening or perforation 70 designed to slidingly fit said rod 13. A coiled spring 26 surrounds a pin 27 in the pointer 22 and normally holds said clutch member 24 away from said pointer, in which position 75 said bent portion 25 binds on said rod 13 and holds the pointer 22 against movement on said rod. When the clutch member 24 is depressed inwardly, said bent portion 25 is released from frictional contact with said 80 rod and said pointer 22 may be moved longitudinally along said rod, for purposes hereinafter stated.

Mounted on the extension 15 of the clip 14 is an adjustable stop or abutment 28. This 85 stop 28 comprises preferably a rod threaded through said extension 15, so that the same may be adjusted toward or away from the pointer 22, in order that said pointer 22 may be kept a predetermined distance from said 90 clip 14, for purposes to be stated.

The operation of my machine is as follows: The record sheet A is first placed over the platen 2, the pins 6 perforating the top edge of said sheet and the inner edge being inserted under the hooked portions 4 of the clips or guides 3. The carbon or other transferring sheet is placed between the frames 7 and 8, said frames then fastened together by the catch 9, and the said frames then folded 100 down and locked in closed position by the latches 11, in which position the record sheet A, the edges thereof extending under the lower frame 7, is firmly held in place. Usually merchandise bills have a space at the 105 top thereof in which is printed the name of the dealer, his address, and other descriptive items, such space being shown at c on sheet C herein. Depending upon the width of such space c, the stop 28 is adjusted in the 110 extension 15 to abut against the pointer 22, so that the space between said pointer 22 and the clip 14 is just equal to the space c, the pointer 22 being used to indicate where to begin to write so that the entries placed on 115 the bill C will be transferred to the unused portion of the record sheet A. The bill C is shown herein in a position where the items placed thereon will be transferred onto the upper portion of the record sheet A, the 120 pointer indicating the top of the unused portion of sheet A and being properly spaced from clip 14 to provide for said space c. When said bill C has been used to the required number of items, the pointer 22 is released from frictional contact with rod 13 125 and moved along said rod to a position slightly below the last written line or entry on said bill, so as to indicate to the operator the top of the unused portion of record sheet 130

A. Bill C is now removed from clip 14, and said clip 14 released from frictional contact with rod 13 and moved along said rod 13 until the stop 28 abuts against the pointer 22. A second bill is now placed in clip 14, and when said second bill is made out and transferred onto sheet A, the same series of operations is gone through with as just described in connection with bill C, in this way 5 no part of the surface of record sheet A being wasted. When one side of a record sheet A is used, the frames 7 and 8 may be readily unlocked and raised and said sheet reversed, in order that both sides thereof may be used, 10 and the frames 7 and 8 again locked in closed position. When sheet A is completely filled, such sheet may be quickly removed and a new sheet placed in proper position, and so on, the sheets A when filled and removed 15 from the machine being designed to be bound in a loose-leaf holder, whereby a complete record or day-book is formed. Whenever it is desired to insert a new carbon or other transferring sheet B, the frames 7 and 8 are 20 easily unfastened and a new sheet B readily inserted and locked in place.

It is obvious that the stop 28 may be adjusted to keep the pointer 22 any predetermined distance from the clip or other paper holding device 14, so that bills with varying widths of space c may be taken care of. It is also obvious that, while I have specifically described the operation of my machine in connection with merchandise bills, it may be 30 used for many other purposes and that minor changes in the arrangement, construction, and combination of the several parts may be made and substituted for those herein shown and described without in the least 35 departing from the nature and spirit of my invention.

Having thus described my invention, what I claim and desire to secure by Letters Patent is:

45 1. In a manifolding device, the combination with a base-plate, of a platen thereon adapted to receive a record sheet, a frame hinged to said base-plate and adapted to surround said platen when in closed position to 50 releasably hold said record sheet in position thereon, a second frame hinged to said first-named frame, said frames forming a holding device for holding a transferring sheet in operative relation to said record sheet, a 55 guide-rod, and a paper-holding device movably mounted on said guide-rod for holding an original entry sheet in operative relation to said transferring and record sheets and adapted to be moved along said guide-rod 60 over said platen; substantially as described.

2. In a manifolding device, the combination with a base-plate, of a platen thereon adapted to receive a record sheet, a frame hinged to said base-plate and adapted to surround said platen when in closed position to

releasably hold said record sheet in position thereon, a second frame hinged to said first-named frame, means for fastening the free ends of said frames together, said frames forming a holding device for holding a transferring sheet in operative relation to said record sheet, means for releasably fastening the free ends of said frames to said base-plate, a guide rod, and a paper-holding device movably mounted on said guide-rod for 70 holding an original entry sheet in operative relation to said transferring and record sheets and adapted to be moved along said guide-rod over said platen; substantially as described. 75

3. In a manifolding device, the combination with a base-plate, of a platen thereon adapted to receive a record sheet, depressible paper-guides mounted on said base-plate for receiving one edge of said record sheet, a frame hinged to said base-plate and adapted to surround said platen when in closed position to 80 releasably hold said record sheet in position thereon, a second frame hinged to said first-named frame, a catch for releasably fastening the free ends of said frames together, said frames when in locked position forming a holding device for holding a transferring sheet in operative relation to said record sheet, a guide-rod mounted on said second frame, a paper-holding device movably mounted on said guide-rod for holding an original entry sheet in operative relation to 85 said transferring and record sheets and adapted to be moved along said guide-rod, and latches for releasably fastening the free ends of said frames to said base-plate; substantially as described. 90

4. In a manifolding device, the combination with a platen adapted to receive a record sheet, of a device adapted to hold a transferring sheet in operative relation to the record sheet, a device adapted to hold an original entry sheet in operative relation to said transferring and record sheets and arranged 105 to be moved over said platen, an indicator adapted to indicate the line of first entry upon the original entry sheet and also arranged to be moved to indicate the line of last entry thereon, and means for limiting the 110 space between said holding device for said original entry-sheet and the indicator when indicating the line of first entry; substantially as described. 115

5. In a manifolding device, the combination with a platen adapted to receive a record sheet, of a device adapted to hold a transferring sheet in operative relation to the record sheet, a device adapted to hold an original entry sheet in operative relation to said 120 transferring and record sheets and arranged to be moved over said platen, an indicator adapted to indicate the line of first entry upon the original entry sheet and also arranged to be moved to indicate the line of 125 last entry thereon; substantially as described. 130

last entry thereon, and an adjustable stop for limiting the space between said holding device for said original entry sheet and said indicator when indicating the line of first 5 entry; substantially as described.

6. In a manifolding device, the combination with a platen adapted to receive a record sheet, of a device adapted to hold a transferring sheet in operative relation to the record sheet, a device adapted to hold an original entry sheet in operative relation to said transferring and record sheets and arranged to be moved over said platen, an indicator adapted to indicate the line of first entry upon the original entry sheet and also arranged to be moved to indicate the line of last entry thereon, an adjustable stop for limiting the space between said holding device for said original entry sheet and said indicator when indicating the line of first entry, and means for releasably securing said holding device and said indicator in their adjusted positions; substantially as described.

7. In a manifolding device, the combination with a base-plate, of a platen thereon adapted to receive a record sheet, a device adapted to hold a transferring sheet in operative relation to the record sheet, a guide-rod located adjacent to one side of said platen and extending lengthwise thereof, a device slidably mounted on said guide-rod for holding an original entry sheet in operative relation to said transferring and record sheets and arranged to be moved along said guide-rod over said platen, an indicator also slidably mounted on said guide-rod adapted to indicate the line of first entry upon said original entry sheet and arranged to be moved on said guide-rod to indicate the line of last entry thereon, and an adjustable stop for limiting the space between said holding device for the original entry sheet and the indicator when indicating the line of first entry; substantially as described.

45 8. In a manifolding device, the combination with a base-plate, of a platen thereon adapted to receive a record sheet, a device adapted to hold a transferring sheet in operative relation to said record sheet, a guide-rod located adjacent to one side of said platen and extending lengthwise thereof, a device 50 slidably mounted on said guide-rod adapted to hold an original entry sheet in operative relation to said transferring and record sheets 55 and arranged to be moved along said guide-rod over said platen, an indicator also slidably mounted on said guide-rod for indicating the line of first entry upon the original entry sheet and movable on said rod for indicating the line of last entry on said entry sheet, means for limiting the space between said holding device for the original entry sheet and the indicator when indicating the 60 line of first entry, and means for releasably 65 securing said holding device and said indicator.

cator in their adjusted positions on said guide-rod; substantially as described.

9. In a manifolding device, the combination with a base-plate, of a platen thereon adapted to receive a record sheet, a device 70 adapted to hold a transferring sheet in operative relation to said record sheet, a guide-rod located adjacent to one side of said platen and extending lengthwise thereof, a paper holding device slidably mounted on 75 said guide-rod adapted to hold an original entry sheet in operative relation to said transferring and record sheets and arranged to be moved along said guide-rod over said platen, an indicator also slidably mounted 80 on said guide-rod for indicating the line of first entry upon the original entry sheet and movable on said rod for indicating the line of last entry on said entry sheet, an adjustable stop for limiting the space between said holding device for said original entry sheet and said indicator when indicating the line of first entry, and clutch mechanisms for releasably securing said holding device and said indicator in their adjusted positions on 85 said guide-rod; substantially as described. 90

10. In a manifolding device, the combination with a base-plate, of a platen thereon adapted to receive a record sheet, of a frame adapted to hold a transferring sheet in operative relation to said record sheet, said frame being adapted to also hold said record sheet in position on said platen, a guide-rod located adjacent to one side of said platen and extending lengthwise thereof, a device slidably mounted on said guide-rod for holding an original entry sheet in operative relation to said transferring and record sheets and arranged to be moved along said rod over said platen, an indicator also slidably mounted on said guide-rod for indicating the line of first entry upon the original entry sheet and movable on said rod for indicating the line of last entry on said sheet, an adjustable stop for limiting the space between said holding device for said original entry sheet and said indicator when indicating the line of first entry, and clutch mechanisms for releasably securing said holding device and said indicator in their adjusted positions on 115 said guide-rod; substantially as described. 95 100 105 110 115

11. In a manifolding device, the combination with a base plate, of a platen thereon adapted to receive a record sheet, a frame hinged to said base-plate and adapted to surround said platen when in closed position to releasably hold said record sheet in position thereon, a second frame hinged to said first-named frame, means for releasably fastening the free ends of said frames together, said frames forming a holding device for holding a transferring sheet in operative relation to said record sheet, means for releasably fastening the free ends of said frames to said base-plate, a guide-rod extending along one 130

side of said platen, a paper holding device 5
slidably mounted on said guide-rod for holding
an original entry sheet in operative relation
to said transferring and record sheets
and arranged to be moved along said rod
over said platen, an indicator also slidably
mounted on said rod for indicating the line
of first entry upon the original entry sheet
and movable on said rod for indicating the
10 line of last entry on said sheet, adjustable
means for limiting the space between said
holding device for said original entry sheet
and said indicator when indicating the line

of first entry, and clutch mechanisms for releasably securing said holding device for said 15
entry sheet and said indicator in their adjusted positions on said guide-rod; substantially as described.

In testimony whereof, I have signed my name to this specification in the presence of 20
two subscribing witnesses.

JOSEPH H. SCHWEICH.
